UNITED STATES PATENT OFFICE.

CHARLES A. CHAYNE, OF HARRISBURG, PENNSYLVANIA.

FLYING-MACHINE.

1,095,080.

Specification of Letters Patent. Patented Apr. 28, 1914.

Application filed July 23, 1913. Serial No. 780,757.

To all whom it may concern:

Be it known that I, CHARLES A. CHAYNE, a citizen of the United States, residing at Harrisburg, in the county of Dauphin and 5 State of Pennsylvania, have invented new and useful Improvements in Flying-Machines, of which the following is a specification.

This invention relates to flying machines 10 of the aerodynamical class, the object of the invention being to provide a flying machine which is light in weight, strong and durable in construction, safe and steady in flight, and adapted to permit of an automatic air 15 shedding action by the wings of the supporting surface, whereby deflection of the machine from a direct line of flight and disturbance of the equilibrium are avoided.

A further object of the invention is to 20 provide a flying machine having a hollow pisciform body or fuselage constructed of superposed wooden strips, giving maximum strength and lightness of weight, with durability and capacity to withstand the 25 strain to which structures of this type are subjected.

A further object of the invention is to 30 provide a novel construction of wings having an automatic flexing action for a variation of the angle of incidence, when struck by a gust or excess air pressures above or below, so as to ward off such excess pressures and prevent the same from acting upon the wings and disturbing the poise or 35 level of flight of the machine.

The invention consists of the features of 40 construction, combination and arrangement of parts herein fully described and claimed, reference being had to the accompanying drawings in which:—

Figure 1 is a side elevation of a flying machine of the monoplane type embodying my invention, a portion of the body or fuselage being broken away to better illustrate the construction. Fig. 2 is a top plan view of the same. Fig. 3 is an enlarged vertical transverse section on line 3—3 of Fig. 1. Fig. 4 is a fragmentary perspective view of the frame of the body showing the method 45 of construction. Fig. 5 is a sectional elevation of one of the wings showing the mode of mounting the ribs upon the wing spar. Fig. 6 is a vertical fore-and-aft section on the line 6—6 of Fig. 4.

50 While in the present disclosure, I have

illustrated my invention as embodied in a monoplane, it will, of course, be understood that the essential features of construction may be embodied in biplanes or other multi-plane machines.

Referring to the drawing, 1 designates the body or fuselage of the machine, which is provided with any suitable type of launching and landing gear. Mounted on this body is a motor 2 for driving a tractor propeller 3. On the tail portion of the body are arranged a vertical rudder 4 and a horizontal rudder or elevator 5, which may be operated by suitable connections with controls arranged within the body.

The body or fuselage 1 is of fusiform or pisciform shape, and provides at its forward portion a car or compartment, having a cockpit 6, for the reception of the aviator's seat, controlling gear, etc. The frame of this body, in accordance with my invention, is made up of a plurality of, preferably three coiled layers or laminations, 7, 8 and 9 of thin wooden strips arranged in superposed relation, with the grain of the strips arranged in crossing planes and preferably with said strips disposed in break-joint relation, whereby a body which is exceedingly light in weight, and is yet of maximum strength and durability, is produced.

Mounted upon the body are wing spars 10 carrying supporting wings 11 reinforced by suitable bracing connections 12 from bracing standards or uprights 13. The wings 11 are suitably curved for the dynamical reaction of the air thereon, and each includes in its construction a series of suitably connected ribs 14, over which is stretched a fabric covering 15 of any preferred material. Each wing 11 is pivotally mounted to have a limited degree of tilting or flexing motion on its supporting spar 10, and for this purpose the ribs 14, which are themselves flexible, are apertured to receive and pivotally engage the spar 10, and each rib is held from sliding motion on the spar by collars 16 suitably fixed to the spar. Fastened to each rib in rear of the spar is a cross piece 17 to which are fixed the rear ends of spring rods or strips 18 disposed in parallel relation on opposite sides of the rib. The forward ends of these spring rods or strips pass through the spar and are held from disconnection by suitable fastening members 19. A spring resistance device is thus provided which 110

normally holds the rib from movement, while permitting the rib under determined pressures to bend or flex in a vertical plane.

It will be understood that the resistance 5 springs of the wings normally maintain said wings at the prescribed supporting angle of incidence. When, however, either wing is struck from below by a volume or current 10 of air of excess pressure, the rear portion of the wing flexes upwardly under such pressure and permits the excess air to escape. By this means the excess pressure is shed, and the machine prevented from tilting laterally or longitudinally and losing its poise 15 or equilibrium. Similarly, if either plane is struck by excess volume of air from above, the rear portion of the wing will flex downwardly and ward off the excess pressure. Steadiness of flight is thus insured, together 20 with a maximum degree of safety against the loss of stability.

I claim:—

1. A flying machine including a body, wing spars carried by the body, wings including ribs pivotally engaging the spars, 25 collars on the spars holding the ribs from

sliding motion, cross pieces on the ribs, and springs on opposite sides of each rib secured at their rear ends to the cross piece and at their forward ends to the spar, said springs 30 being adapted to permit the ribs to have a certain amplitude of flexing motion.

2. A flying machine including a body, hollow wing spars carried by the body, wings including ribs pivotally engaging the spars, 35 collars on the spars holding the ribs from sliding motion, cross pieces on the spars, and linear springs on opposite sides of each rib secured at their rear ends to the cross piece and passing at their forward end through the hollow spar, and fastening means securing the forward ends of the springs to the spar, said springs being adapted to permit the ribs to have a certain 40 amplitude of flexing motion.

In testimony whereof I affix my signature in presence of two witnesses.

CHARLES A. CHAYNE.
